UNITED STATES PATENT OFFICE.

HERBERT W. LAMB, OF LAGRANGE, INDIANA, ASSIGNOR TO FRANK E. ROZELLE, OF LAGRANGE, INDIANA.

PROCESS OF AND APPARATUS FOR COLORING FABRIC.

Application filed September 7, 1922. Serial No. 586,566.

To all whom it may concern:

Be it known that I, HERBERT W. LAMB, a citizen of the United States, residing at Lagrange, in the county of Lagrange and 5 State of Indiana, have invented certain new and useful Improvements in Processes of and Apparatus for Coloring Fabric, of which the following is a specification.

This invention relates to improvements in 10 the art of coloring fabrics, such as tapestry or the like.

The object of the invention is to provide a process and apparatus for treating the fabric upon which the developed color 15 has been applied without pre-heating the same, the effect of such treatment being that the said color will be made fast or capable of permanently withstanding exposure to light and other agencies tending to fade 20 the same.

It is known that certain coloring matter may be made fast by applying the same to the fabric while heated, or by using a mordant, but such processes are more or 25 less uneconomical and attended with considerable inconvenience in the performance thereof.

In my improved process I contemplate applying the coloring matter to the tapestry 30 or other fabric with a brush in the desired design, or by other approved means, without first heating the said coloring matter. After the coloring matter has been allowed to dry or set, the fabrics are placed 35 in a press with damped absorbent material, such as blotting paper, interposed between the pieces of colored fabric, care being exercised in arranging the materials in such manner that the application of pressure thereto will be substantially uniform 40 throughout the colored area thereof, and that wrinkles are eliminated. The absorbent material should be damped with water or by a chemical solution which may be found 45 to be of advantage under certain conditions, such moisture acting as a solvent for or to soften the coloring matter when the fabric is subjected to heat and pressure; but such moisture must not be in such quantity 50 that the coloring matter will become so fluid as to spread and destroy the design

in which it was applied to the fabric. After the colored fabric is positioned on the base or support of the press, which support may be positioned in or subsequently removed to 55 a chamber or heater provided with a suitable door capable of being tightly sealed, pressure is gradually applied to the material by tightening the press, which is provided with a screw stem having an actuating handle or wheel exterior of said heater. Heat, preferably by means of steam, is admitted to the heater during the pressure treatment, the pressure being increased 60 gradually during the process. After an interval of such application of heat and pressure it will be found that the fibres of the fabrics so treated will have become thoroughly 65 impregnated with the coloring matter, which will be capable of resisting the fading effects of light and cleansing operations. 70

In the accompanying drawing I have illustrated diagrammatically one form of apparatus for carrying out my process, but it will be understood that I do not restrict 75 myself to the use of this particular arrangement.

In the drawing—

10 is a heater communicating through pipe 11 with a suitable source—not shown—80 of steam or the like, said pipe being provided with a regulating valve 11^a. An exhaust conduit 12, having a valve 13, is also provided for permitting the heating fluid to escape from the heater when desired. A 85 supporting base 14 is provided for supporting the layer of colored fabric 15 with the interposed layers of absorbent material 16 during the pressing and heating treatment.

The fabric and absorbent materials may be 90 arranged on the support 14 prior to the insertion of the latter into the heater, if desired. A pressing plate 17 is carried and actuated by means of a threaded stem 18, which is provided with a manually operable 95 wheel 19, or the like, exterior of said heater, as shown. When the fabric and absorbent materials are positioned under plate 17, upon the support 14, the door 20 of the heater 10 is closed, and heated vapor or steam under 100 pressure, as may be found more desirable, is admitted to the heater through pipe 11 by

opening valve 11^a. A pressure gauge 10^a and thermometer 10^b may be provided, if desired, to indicate the steam pressure and temperature, respectively, in the heater. 5 Conduit 12 may be closed by valve 13, or circulation of the heating fluid may be effected by opening the same, if desired. During the heating of the fabric the operator gradually turns the hand wheel 19 to increase the pressure on the material being treated, which pressure, co-operating with the action of the heating fluid and the moisture of the absorbent materials 16, causes the coloring matter to soften or go into solution and forces the same thoroughly into the pores of the fabric.

In order that the pressure may be properly applied throughout the coloring process I provide a pressure gauge 8 adapted to indicate the pressure exerted on the fabric by the actuation of the wheel 19. The gauge may be positioned on the top of heater 10 and communicates through a flexible tube 8^a with coacting compressible diaphragms 9, 9 which are interposed between the plate 17 and stem 18 as shown. The chamber formed by the said diaphragms 9, 9 is filled with fluid, which is displaced in quantities proportional to the applied pressure, such displacement being effected through the tube 8^a. Suitable mechanism (not shown) of the gauge 8 is actuated by the displaced fluid to indicate, by means of the pointer 8^b, the pressure applied to the fabric.

35 It will be seen that the rapidity with which the coloring matter is caused to go into solution may be controlled by the operator by regulating the application of pressure to the fabric or fabrics being treated, and that with my process the coloring matter will be caused to enter the pores of the fabric and become permanently fixed or fast without running or impairing the design in which it was applied.

40 45 After the coloring matter has been subjected to the above described treatment over a sufficient period, the valve 11^a is closed and the heating fluid permitted to escape through conduit 12, and the fabric removed from the heater.

50 It will be obvious that my process is economical and is more convenient than the use of mordants in fixing the colors or in the application to the fabric of the colors while heated. It will also be obvious that various changes may be made in the above described invention without departing from the spirit thereof; and I do not, therefore, wish to be restricted to the specific steps described, except where limitations appear in the appended claims.

I claim:—

1. The process of coloring fabrics or the like, which consists in applying color to said fabrics, arranging said colored fabric

between layers of moistened absorbent material, and thereafter applying heat to said fabric and said absorbent material.

2. The process of coloring fabrics or the like, which consists in applying coloring matter thereto, arranging said colored fabric between layers of absorbent material, and thereafter applying pressure to said fabric and said absorbent material.

3. The process of coloring fabrics, which consists in applying coloring matter thereto without first heating said coloring matter, arranging said colored fabric between layers of porous materials, and thereafter subjecting said fabric and porous materials to heat and pressure.

4. The process of coloring fabrics, which consists in applying unheated coloring matter thereto, arranging said colored fabric between layers of moistened porous material, and thereafter subjecting said fabric and porous materials to heat and pressure.

5. The process of coloring fabrics or the like, which consists in applying unheated coloring matter thereto, placing said colored fabric in a heater between layers of moistened porous materials, and thereafter subjecting said fabric and porous materials to heat and gradually increasing pressure.

6. The process of coloring fabrics, which consists in applying coloring matter thereto, arranging said colored fabric between layers of moistened porous material, and thereafter subjecting said fabric and porous materials to heat and varying pressure.

7. The process of treating colored fabrics or the like, which consists in arranging said fabric between layers of moistened porous material, subjecting said fabric and porous material to pressure and heat, and varying said pressure during the application of said heat.

8. The process of treating colored fabrics or the like, which consists in arranging said fabric between layers of moistened porous material, subjecting said fabric and porous material to varying pressure in a heater, and admitting a heating fluid thereto during the pressing operation.

9. The process of coloring fabrics, which consists in applying developed coloring matter thereto, and thereafter rendering said colors fast by simultaneously subjecting the colored portions of said fabrics to heat and pressure.

10. The process of coloring fabrics of the like, which consists in applying coloring matter thereto, and arranging said colored fabric between layers of absorbent material and thereafter treating said fabric to fix the colors thereof.

11. The process of coloring fabric or the like, which consists in applying coloring matter thereto and thereafter treating said fabric to fix the color thereof, said treat-

ment comprising the application of varying pressure to said fabric.

12. The process of coloring fabric or the like, which consists in applying coloring matter thereto, applying moisture to said colored fabric and thereafter applying heat thereto.

13. The process of coloring fabric or the

like which consists in applying coloring matter thereto applying moisture to said colored fabric and thereafter applying heat thereto.

In testimony whereof, I have subscribed my name.

HERBERT W. LAMB.
